TRENCHING MACHINE

Robert H. McBean, Cleveland, Ohio, assignor to
The Cleveland Trencher Company, Cleveland,
Ohio, a corporation of Ohio

Application March 27, 1941, Serial No. 385,431

12 Claims. (Cl. 37-97)

This invention relates to an excavating or trench digging machine, and more particularly to an improved trench digging machine having a digging unit which is adapted and arranged to be adjustably lowered to determine the depth of the trench to be dug or which may be raised above the machine supporting surface to facilitate movement of the machine from place to place, and wherein the positioning of the digging unit is accomplished by the operation of a minimum number of controls to thereby simplify the operation of the machine. This, therefore, is the general object of the present invention.

A more specific object of this invention is to provide trench digging or excavating machine with an improved mechanism for positioning the digging unit.

A further object of the present invention is to provide an improved arrangement for supporting the digging unit of a wheel type trenching machine together with an improved power operated mechanism for adjustably positioning the digging wheel relative to the machine supporting surface.

Other objects and features of this invention will become more apparent from the following description, reference being had to the accompanying drawings, wherein I have shown a preferred embodiment of the invention. The essential and novel features of the invention will be summarized in the claims.

In the drawings, Fig. 1 is a side elevation of a trench digging machine constructed in accord with the present invention; Fig. 2 is a side elevation similar to Fig. 1, but illustrating the digging unit in a different position relative to the machine itself; Fig. 3 is a substantially vertical section as indicated by the lines 3-3 on Fig. 1; Fig. 4 is an enlarged sectional detail, the plane of the section being indicated by the lines 4-4 on Fig. 3; and Fig. 5 is a fragmentary view similar to Fig. 1, but illustrating a modified form of the invention.

Referring to the drawings and particularly Fig. 1, the trench digging machine with which the present invention is particularly concerned comprises in general a main frame 10, mounted on a pair of tractor belt supports, one of which is shown in Fig. 1 at 12. The supports 12 are each provided with a wheel 13 and a sprocket wheel 15 about which an endless tractor belt chain 16 is looped in the usual manner. Suitable rollers or wheels 18, mounted on the supports 12, coast with the belt intermediate the sprocket wheel 15 and wheel 14 to distribute the load of the ma-

chine along the entire lower stretch of the tractor belt.

Mounted at the extreme forward end of the frame 10, and disposed forwardly of the tractor belts is a motor, such as a gasoline engine 17 of the automotive type. At the rearward end of the machine there is an inclined guideway 20. As shown in the drawings, the lower end of this guideway is mounted on the rearward end of the frame 10 and extends upwardly and forwardly to a point which, as shown, is above the tractor belts. Suitable bracing struts 21 are provided to insure rigidity of the structure. The guideway 20 supports, as will hereinafter be more fully described, a rearwardly extending supplemental frame or boom 25 which carries a digging or excavating unit 26.

The digging unit supporting frame or boom 25 comprises a pair of longitudinally extending spaced frame members 27 which are connected at their opposite ends by cross frame members, one of which is shown in Fig. 3 at 28. At its forward end, the boom 25 is pivotally connected, as by pivot pins 30, to a carriage 31. This carriage is slidably mounted for vertical movement in the guideway 20, which as shown in Fig. 4, comprises a pair of inwardly faced channel members 32. Preferably, the carriage comprises two pairs of channel members 35, secured together at their upper and lower ends by cross members 36, and provided with front and rear plates 37, thus forming an enclosed box-like structure.

The digging unit or digging wheel comprises a pair of spaced metal rings, one of which is shown in Fig. 1 at 40. These rings are spaced by a plurality of U-shaped digging buckets 41. The wheel is disposed between the frame members and is supported at three points by pairs of rollers 42 which engage the respective rings 40. These rollers are mounted on suitable shafts journalled in bearings carried by frame struts 43, which form part of the supplemental frame 25.

The digging wheel 26 and tractor belts 16 are driven by the engine 17. A chain, indicated at 23 on Figs. 1 and 2 couples the engine with the sprocket wheels 15 of the tractor belt assembly. A power transmission mechanism generally indicated at 45 is interconnected between the engine and a driving sprocket 47. A lever 46 is provided to control the application of power to the sprocket 47. A driving chain 48 transmits the power from the sprocket 47 to a sprocket wheel 49, carried by the supplemental frame 25 and arranged to engage teeth like formations 50 se-

cured to the ring 40, as generally indicated in Fig. 1. A more complete description of the digging wheel, the digging wheel driving mechanism, as well as a conveyor 51 for ejecting the dug material may be had from reference to the co-pending application of Vincent S. Penote and Albert R. Askue, Serial No. 299,306, filed October 13, 1939.

As heretofore mentioned, the inner or forward end of the boom or supplemental frame 25 is pivotally supported by the carriage 31. The outermost or rearward end of this boom is preferably supported by a pair of cables 60. As indicated in Fig. 1, the end of each of these cables is secured to the outer end of the supplemental frame 25, as at 61 and the other end of each cable is secured, as indicated in Fig. 4, to the respective winding drums 62. These drums are drivingly secured to opposite ends of a cross shaft 63 mounted in bearings 64, carried by a plate 65 which is secured, as by welding, to the front plate 31 of the carriage 31.

Rotation of the cable winding drums 62 results from relative movement between the carriage 31 and its guideway 20. Secured to the shaft 63 are a pair of gears 66. These gears are drivingly connected with the respective winding drums 62, and are arranged to engage the respective toothed racks 67, which are secured to the side walls of the vertical guideway members 32, as is illustrated in Fig. 4.

The raising and lowering of the supplemental frame 25 and the digging wheel 26 carried thereby is accomplished by a single operating means. As shown in Fig. 3, a hydraulic cylinder 70 is secured to the frame 10 and extends upward between the guideway channels 32. Suitable conduits, such as indicated at 71, extend from the cylinder 70 to a hydraulic pump 72, driven by the motor 17 in any suitable manner. A valve mechanism, not shown but controlled by a lever 73 is interposed in the conduit 71 to enable the control of the flow of fluid to and from the cylinder 70. The cylinder 70 is provided with a piston (not shown) having a plunger 74 which extends upward through the cylinder and is secured, as indicated at 75, to the upper end of the carriage 31.

The operation of the hydraulic piston mechanism thus moves the supplemental frame 25 and digging wheel 26 from the position shown in Fig. 1 to the position shown in Fig. 2, or vice versa. It is to be noted that as the wheel is raised from the position shown in Fig. 2, the movement of the carriage 31 upwardly in the guideway 32 results in the rotation of the shaft 63 due to the engagement of the gear 66 with the rack 67 carried by the guideway. This results in a constant reeling in of the cables 60, and causes the outermost end of the digging wheel frame 25 to be raised at a higher rate of speed than the inner end, thus automatically rocking the digging wheel about its pivotal connection with the carriage and assisting materially in decreasing the overall length of the machine.

While I have described a cable winding mechanism as a preferred form of supporting and raising mechanism for raising and lowering the outer end of the boom 25, I nevertheless consider other forms of mechanism within the spirit of the present invention. In Fig. 5, I have shown a fragmentary view of a modified form of the invention. In this form rigid bars 60a are used

to support the outer end of the digging wheel boom 25.

Each bar 60a is pivotally connected at 61a with the outer end of the boom or digging wheel frame 25, and extends inward to the gear and rack mechanism 66-67 carried by the carriage 31 and guideway 20, respectively. In this form of the invention, gears 80 replace the winding drums 62 on the shaft 63. These gears engage rack formations on the respective bars 60a and serve to rock the boom or supplemental frame 25 about its pivots 30 consequent upon relative movement between the carriage and the guideway.

Each bar 60a is maintained in engagement with its respective gears 80 by a pair of rollers 81 which engage the upper surface of the respective bar. The rollers are journaled in a U shaped bracket 82 which embraces the respective bar 60a and gear 80, and has its legs journaled on the gear shaft 63 heretofore described.

I claim:

1. A trenching machine, a frame carried by propelling and supporting members, a motor on said frame, driving connections between said motor and said propelling members, a substantially upright guideway mounted on said frame adjacent one end thereof and extending upwardly and inwardly from said frame, a carriage slidably mounted in said guideway, a digging mechanism, a support for said digging mechanism, one end of said support being pivotally mounted on said carriage, means acting on said carriage and operated by said motor to raise and lower said carriage, means interconnecting the carriage and the outer end of said support, and gear means operated by relative movement between the guideway and carriage and coacting with said connecting means to rock the support in response to the movement of the carriage in said guideway.

2. A trenching machine, a frame carried by propelling and supporting members, a motor on said frame, driving connections between said motor and said propelling members, a substantially upright guideway mounted on said frame adjacent one end thereof and extending upwardly and inwardly from said frame, a digging mechanism, a support for said digging mechanism, one end of said support being pivotally mounted on said carriage, means acting on said carriage and operated by said motor to raise and lower said carriage, means interconnecting the carriage and the outer end of said support, and gear means operated by relative movement between the guideway and carriage and coacting with said connecting means to rock the support in response to the movement of the carriage in said guideway.

3. In a trenching machine a frame carried by propelling and supporting members, a motor on said frame, driving connections between said motor and said propelling members, said frame including horizontal frame members and an up-standing guideway, a carriage mounted in said guideway, a digging mechanism, a support for said digging mechanism, one end of said support being pivotally mounted on said carriage and extending outwardly therefrom, means acting on the carriage and operated by said motor to raise and lower said carriage, gears operated by the movement of the carriage in the support, and means actuated by said gearing to raise and lower the outer end of said support relative to the guideway and in response to the raising and

lowering of the carriage and at a greater rate of speed than the movement of the inner end of the carriage.

4. In a trenching machine a frame carried by propelling and supporting members, a motor on said frame, said frame including an upstanding guideway, a carriage mounted in said guideway, a digging mechanism, a support for said digging mechanism, one end of said support being pivotally mounted on said carriage, means acting on the carriage and operated by said motor to raise and lower said carriage, a rack mounted on said guideway, a gear carried by said carriage and meshing with said rack whereby the gear is rotated by movement of the carriage in the guideway, and means actuated by the rotation of said gears to rock the support relative to the carriage and in response to the raising and lowering of the carriage in the guideway.

5. A trenching machine, a frame carried by propelling and supporting members, a motor on said frame, an upwardly extending guideway mounted adjacent one end of said frame, a carriage slidably mounted for up and down movement in said guideway, a digging mechanism, a support for said digging mechanism, said support having a pivotal connection with said carriage and extending outwardly therefrom, means acting on said carriage and operated by said motor to raise and lower said carriage, a cable winding mechanism mounted on said carriage, said winding mechanism being actuated to wind or unwind a cable by movement of the carriage in the guideway, a cable extending from said winding mechanism to the outer end of said support, whereby the support will be rocked about its pivotal connection with the carriage whenever the carriage moves in said guideway.

6. A trenching machine, a frame carried by propelling and supporting members, a motor on said frame, an upwardly extending guideway mounted on said frame, a carriage slidably mounted in said guideway, a digging mechanism, a support for said digging mechanism extending outward from said carriage, a pivotal connection between one end of said support and said carriage, means acting on said carriage and operated by said motor to raise and lower said carriage, a rack on said guideway, a gear on said carriage and in engagement with said rack whereby relative movement between the carriage and guideway rotates said gear, a cable winding drum mounted on said carriage and driven by said gear, and a cable extending from said drum to the outer end of said support.

7. A trenching machine, a frame carried by propelling and supporting members, a motor on said frame, an upwardly extending guideway mounted on said frame adjacent one end thereof, a carriage slidably mounted in said guideway, a digging mechanism, a support for said digging mechanism, one end of said support being pivotally connected to said carriage, means acting on said carriage and operated by said motor to raise and lower said carriage, rigid means interconnecting the carriage and the outer end of said support and operated by relative movement between the guideway and support to raise and lower the outer end of the support in response to the movement of the frame in said support and at a greater rate of speed than the movement of the inner end of said support.

8. In a trenching machine, a frame carried by propelling and supporting members, a motor on said frame, said frame including horizontal

frame members and an upstanding guideway, a carriage mounted in said guideway, a digging mechanism, a support for said digging mechanism extending outward from said carriage, one end of said support being pivotally mounted on said carriage, means acting on the carriage and operated by said motor to raise and lower said carriage, gearing operated by the movement of the carriage in the support, and rigid means actuated by said gearing to rock said support relative to said carriage and in response to the raising or lowering of the carriage in the guideway.

9. A trenching machine, a frame carried by propelling and supporting members, a motor on said frame, a guideway mounted adjacent one end of said frame and extending upwardly and inwardly therefrom, a carriage slidably mounted in said guideway, a digging mechanism, a support for said digging mechanism, one end of said support having a pivotal connection with said carriage, means operated by said motor to raise and lower said carriage, a rack secured to said guideway, gearing carried by said carriage and engaging said rack whereby relative movement between the carriage and guideway will rotate said gearing, a bar having one end pivotally connected to the outer end of said support and having a rack formation on its inner end to engage said gearing, whereby said support will be rocked about its pivotal connection consequent upon movement of the carriage in the guideway.

10. In a trenching machine, a main frame, a guideway mounted thereon adjacent one end thereof and extending upwardly therefrom, a digging mechanism, a support for said digging mechanism, a carriage slidably mounted in said guideway for relatively vertical movement therein, the inner end of said support being pivotally secured to said carriage, means acting on said carriage to raise and lower the same in the guideway, a shaft mounted in said carriage, gearing interconnecting said shaft with the guideway, and operative to rotate the shaft consequent with movement of the carriage in the guideway, a winding drum carried by said shaft, and a flexible member having one end thereof secured to said winding drum and the other end to a point adjacent the outer end of said support, whereby the support will be rocked about its pivotal connection with the carriage in response to the movement of the carriage in the guideway.

11. In a trenching machine, a main frame, a guideway mounted thereon adjacent one end thereof and extending upwardly therefrom, a digging mechanism, a support for said digging mechanism, a carriage slidably mounted in said guideway for relatively vertical movement therein, the inner end of said support being pivotally secured to said carriage, means acting on said carriage to raise and lower the same in the guideway, a shaft mounted in said carriage, gearing interconnecting said shaft with the guideway, and operative to rotate the shaft consequent upon movement of the carriage in the guideway, a gear carried by said shaft, a rack member having one end thereof in engagement with said last-named gear and the other end pivotally connected to the outer end of said support, whereby the support will be rocked about its pivotal connection with the carriage in response to the movement of the carriage in the guideway.

12. In a trenching machine, a main frame, a guideway mounted thereon adjacent one end

thereof and extending upwardly therefrom, a digging mechanism, a support for said digging mechanism, a carriage slidably mounted in said guideway for relatively vertical movement therein, the inner end of said support being pivotally secured to said carriage, hydraulic means acting on said carriage to raise and lower the same in the guideway, a pair of racks fixed to opposite sides of said guideway, a shaft mounted in said carriage, a gear at each end of said shaft and meshing with respective racks, whereby the shaft

will rotate whenever the carriage moves in the guideway, a pair of winding drums carried by said shaft, and a pair of flexible members each having one end thereof secured to a respective winding drum and the other end to a point adjacent the outer end of said support, whereby the support will be rocked about its pivotal connection with the carriage in response to the movement of the carriage in the guideway.

10

ROBERT H. McBEAN.
